(57) **CLAIM**

The ornamental design for a combination bow sight and range finder, as shown and described.

DESCRIPTION

FIG. 1 is a front elevation view of a combination bow sight and range finder showing my new design;

FIG. 2 is a rear elevation view thereof;

FIG. 3 is a right elevation view thereof;

FIG. 4 is a left elevation view thereof;

FIG. 5 is a top plan view thereof;

FIG. 6 is a bottom plan view thereof; and,

FIG. 7 is an isometric view thereof.

The broken line showing of portions of the combination bow sight and range finder in FIGS. 1 and 7 forms no part of the claimed design.

The activation switch cord portion of the design shown in FIGS. 1 through 4 and 7 is shown broken away in order to indicate that a specific length of this portion forms no part of the claimed design.
